CLAIM

The ornamental design for table lamp, as shown and described.

DESCRIPTION

2. Table lamp
4. Table lamp
2.1 : Perspective
2.2 : Front
2.3 : Top
2.4 : Bottom
4.1 : Perspective
4.2 : Front
4.3 : Top
4.4 : Bottom

(Continued)

The table lamp comprises a lamp shade with different outer contours emitting light in a downward direction and having beneath the lamp shade a conical elastic fixing member; the lamp shade has a round power button at the top center and a covered charging connector at the bottom; the left side views, the right side views and the back views are omitted because they are identical with the front views, respectively.
